UNITED STATES PATENT OFFICE.

DANIEL J. MURNANE, OF SAN MATEO, AND DANIEL J. MURNANE, JR., OF SAN FRANCISCO, CALIFORNIA, ASSIGNORS TO NON-PRESSURE GLAZING COMPANY, OF SAN FRANCISCO, CALIFORNIA, A CORPORATION OF CALIFORNIA.

SASH FOR HOLDING GLASS.

Application filed September 16, 1925. Serial No. 56,655.

Our invention relates to metallic sashes for holding the glass of windows and show cases and particularly to sashes for holding large and heavy sheets of plate glass.

5 One of the objects of the invention is the provision of a sash which exerts no clamping action upon the glass.

Another object of the invention is the provision of improved and simplified sash members.

Another object of the invention is the provision of improved means for securing the sash members together.

Another object of the invention is the provision of a sash of the character described readily and cheaply formed from sheet metal and having a minimum number of parts, which can be assembled by a few simple operations to hold the glass securely without pressure thereon.

The invention possesses other objects and features of advantage, some of which, with the foregoing, will be set forth in the following description of the preferred form of 25 our invention which is illustrated in the drawings accompanying and forming part of the specification. It is to be understood that we do not limit ourselves to the showing made by the said drawings and description, as we 30 may adopt variations of the preferred form within the scope of our invention as set forth in the claims.

Referring to the drawings:

Figure 1 is a vertical sectional view thru 35 the sash of our invention, showing a plate of glass held herein.

Figure 2 is a perspective view of the tie bar embodied in our invention.

Figure 3 is a sectional view thru a portion 40 of the tie bar, the plane of section being indicated by the line 3-3 of Figure 2.

Figures 4 and 5 are vertical sectional views showing the means for supporting the glass in the sash. Figure 4 shows the parts after 45 the glass has been set in the sash, but before it has been moved to its final position, and Figure 5 shows the parts in final position.

Figure 6 is a vertical sectional view, showing a modified form of our invention, particularly as it relates to the means for locking the tie bar.

Figure 7 is a perspective view of the modified form of tie bar from the structure shown in Figure 6.

Figure 8 is a sectional view thru a portion 55 of the tie bar shown in Figure 7, the plane of section being indicated by the line 8-8 of Figure 7.

Figure 9 is a perspective view of the non-slip conformable plate embodied in the structure shown in Figure 6.

In general terms the sash of our invention comprises a stationary sash bar adapted to engage one side of the glass, and an adjustable sash bar adapted to engage the other side 65 of the glass. Each of these members is formed in one piece, the stationary sash bar including a raised seat and a lower foot flange resting upon the supporting structure. At intervals tie bars extend from the adjustable 70 sash bar to the seat. One end of the tie bar is permanently secured to the adjustable sash bar, and means are provided for clamping the other end to the seat to hold the sash bars 75 together with the glass therebetween. The

end of the tie bar adjacent the seat is of conformable character, and the clamping means comprises a headed screw, the head of which embeds itself in the end of the tie bar. This occurs without placing the least tension 80 on the tie bar so that there is no tendency to put a pressure upon the glass when the parts are assembled. Improved means are provided for giving the conformable character to the tie bar end and also for securing the tie bar in the adjustable sash bar. Improved setting blocks are also provided 85 for permitting the setting of the glass in the sash, and these setting blocks remain in the sash as permanent supports for the glass. 90

In greater detail our invention comprises a stationary sash bar having the wall portion 2 adapted to be secured by screws 3 to the supporting structure 4. Along its upper edge, the wall 2 is extended in a top flange 95 6, terminating in an inwardly turned glass-engaging flange 7. At its lower edge the wall 2 is extended in a base flange comprising the raised seat portion 8 and the foot flange 9, the latter of which rests upon the supporting 100 structure. It will be noted that the entire stationary member comprising the portions 2, 6, 8 and 9 are formed integrally, and preferably by rolling from a single sheet of suitable material. At intervals the seat 8 is provided with screws 11 threaded therein. The screws are provided with large heads 12, and if desired may be coned on the under side to 105

correspond with conical depressions in the bottom of which the screws are threaded.

Resting on the foot flange 9 of the stationary sash bar is the adjustable sash bar 5 16, having at its upper edge the inwardly turned glass-engaging flange 17, and at the lower edge the inwardly turned base flange 18, from which is turned up the tab 19. Interlocked within the adjustable sash bar is the 10 foot of the tie bar, the end 21 being engaged behind the flange 17. Formed in the tie bar is an aperture 22 which is engaged by the tab 19, so that the tie bar is securely interlocked within the adjustable sash bar. The 15 free end of the tie bar is provided with a slot 23 bordered with corrugations 24. In use the slotted end of the tie bar slides under the head 12 of the clamping screw and when the screw is tightened, the head imbeds itself in the corrugated portions of the tie bar and 20 locks it securely in place without placing any tension on it tending to put undesired strains on the glass 25. The tie bar as a whole is an angular member and to prevent 25 flexing between the parts thereof, we provided flanges 26 along the edges so that rigidity is assured.

Instead of corrugating the end of the tie bar, we may form the tie bar end with a 30 roughened or toothed surface, for example, by punching thru the metal as shown in Figures 7 and 8, to leave upstanding beads or teeth 31. When this form of tie bar is used, we interpose a conformable plate or washer 35 32, conveniently made of lead, between the roughened surface of the tie bar and the head of the screw, so that the pressure of the screw causes the head thereof to embed itself slightly in the lead and at the same-time press the 40 lead upon the roughened surface of the tie bar, thus locking all securely together. We show this construction in Figure 6, and it will be observed that the under side of the screw head and the seat on which the tie bar rests are both flat.

It will of course be understood that the tie bars are placed at intervals along the sash and in sufficient numbers to insure the integrity of the sash structure as a whole.

50 In order to permit ready access to the screws, when the glass is being set in the sash, an aperture 37 is left in the top flange 6 above each screw.

When the glass is placed within the sash 55 it is set upon blocks 38 formed as shown in Figures 4 and 5 and preferably provided with a leather facing 39 upon which the glass directly rests. One of these blocks is conveniently placed about every four feet in the 60 sash, and after the glass has been set on the blocks as indicated in Figure 4 it may be pushed up against the flange 7, the blocks forming shoes and sliding into the position

shown in Figure 5, where they remain as permanent supports for the glass.

65

We claim:

1. In a sash for holding glass, a stationary sash bar comprising a wall adapted for connection to the supporting structure, a top flange integral with the wall and forming a fixed glass-engaging edge, a base flange integral with the wall and providing a tie bar seat, an adjustable sash bar adapted to engage the opposite side of the glass, a tie bar interlocked with the adjustable sash bar and extending over said seat, and means for locking the tie bar to the seat.

70

2. In a sash for holding glass, a stationary sash bar comprising a wall adapted for connection to the supporting structure, a top flange integral with the wall and adapted to engage one side of the glass, a base flange integral with the wall and providing a raised tie bar seat and a lower foot flange adapted to rest on the supporting structure, an adjustable sash bar adapted to engage the opposite side of the glass, a tie bar interlocked with the adjustable sash bar and extending over said seat, means for locking the tie bar to the seat, and L-shaped supporting blocks for the 80 glass slidable on said seat and foot flange.

85

3. A sash for holding glass comprising a stationary sash bar, a seat arranged on the stationary sash bar, an adjustable sash bar having an inwardly turned glass-engaging flange on one edge and an inwardly turned tab adjacent the other edge, an angular tie bar having one side extending over said seat and apertured to engage said tab and having the end of the other side engaged behind said glass-engaging flange, and means for locking the tie bar on said seat.

95

4. A sash for holding glass comprising a stationary sash bar, a seat arranged on the stationary sash bar, an adjustable sash bar having an inwardly turned tab thereon, an angular tie bar having one side extending over said seat and apertured to engage said tab, means for locking the tie bar on said seat, and a foot on the tie bar engaged within 100 said adjustable sash bar.

105

5. A sash for holding glass comprising a stationary sash bar, a seat arranged on the stationary sash bar, an adjustable sash bar having an inwardly turned tab thereon, an L-shaped tie-bar having the horizontal member extending over said seat and apertured to engage said tab, means for locking the horizontal member on said seat, the vertical member of the L being engaged within said adjustable sash bar, and a continuous stiffening flange on opposite edges of the tie bar.

115

In testimony whereof, we have hereunto set our hands.

DANIEL J. MURNANE.

DANIEL J. MURNANE, JR.
